US0D1044236S

(12) United States Design Patent (10) Patent No.: US D1,044,236 S
(45) Date of Patent:  Oct. 1, 2024

(54) SHOE

(71) Applicant: NIKE, Inc., Beaverton, OR (US)

(72) Inventor: Enrico Carbonere, Hillsboro, OR (US)

(73) Assignee: NIKE, Inc., Beaverton, OR (US)

() Term: 15 Years

(21) Appl. No.: 29/888,516

(22) Filed: Mar. 31, 2023

(51) LOC (14) Cl. 02-04

(52) U.S. Cl.

USPC D2/951; D2/948; D2/954

(57)

CLAIM

The ornamental design for a shoe, as shown and described.

DESCRIPTION

The FIGURE is a bottom view of a shoe showing my new design.

The stipple shading and their respective solid line boundaries represents a surface ornamentation pattern. The broken line showing of the remainder of the shoe forms no part of the claimed design.

1 Claim, 1 Drawing Sheet
